UNITED STATES PATENT OFFICE.

CHARLES F. PYM, OF ESSEX, ONTARIO, CANADA, ASSIGNOR OF ONE-HALF TO KRENTLER BROTHERS COMPANY, OF DETROIT, MICHIGAN, A CORPORATION OF MICHIGAN.

LASTING-MACHINE.

1,010,800.

Specification of Letters Patent.

Patented Dec. 5, 1911.

Application filed December 3, 1910. Serial No. 595,423.

To all whom it may concern:

Be it known that I, CHARLES F. PYM, a subject of the King of Great Britain, and resident of Essex, in the Province of Ontario, Dominion of Canada, have invented an Improvement in Lasting-Machines, of which the following description, in connection with the accompanying drawings, is a specification, like letters on the drawings representing like parts:

In that type of lasting machine in which the shoe is supported with a capability of more or less movement, particularly in the wiper type of machine, considerable difficulty is experienced at times in properly positioning and holding the shoe. Accordingly my invention aims to provide, in connection with lasting mechanism, special means for co-operating with said lasting mechanism in securing the perfect lasting of the shoe without any possibility of improper shifting or moving of the shoe during the lasting operation.

I have herein illustrated my invention particularly with reference to the lasting of the toe. Such a lasting machine requires that the toe of the last shall be gripped above and below and thereby held against the complex thrust of the wipers, which is mainly in a direction from the toe to the heel, but as the top and bottom lines of an ordinary last verge toward each other from the instep to the toe, so that the last is wedge shaped when viewed sidewise, it has been heretofore necessary to grip the shoe bottom side up in the machine with an upper clamp against the bottom of the shoe in opposition to a lower clamp or rest against the shoe upper (between the toe and the instep) with a pressure sufficiently severe to prevent the displacement of the shoe under the thrust or pressure of the wipers. This clamping pressure is such that it frequently injures the shoe and also brings an undue strain on the machine, and requires a positiveness of movement and of grip which increases the difficulty of lasting.

To obviate those disadvantages and afford a greater freedom of position and absence of strain on the last I have provided a supporting means, operating in conjunction with the wiping mechanism to accomplish two principal objects, first, a positive endwise resistance to the thrust of the wipers (preferably

including also resistance to sidewise thrusts), and, second, the maintenance of a gripping engagement or pressure on the bottom of the shoe at or about a fixed locating point adjacent the toe whereby the wiping action is facilitated.

In the preferred construction of my invention as herein shown, I take advantage of the fact that all lasts have a slope at the shank and an opposing hollow on top of the shoe (between the toe and instep), and I locate a foot or engaging part in position to engage the last or shoe at and against this slope of the shank. I provide also a support to rest against the hollow on the top of the last as mentioned, and another support or gripper to engage the bottom of the shoe at that point with relation to the wipers which it is desired shall constitute a locating point for the wiper action, etc., and preferably a fourth support at the heel.

My invention will be more clearly apprehended in the course of the following description, taken with reference to the accompanying detailed drawings, in which I have illustrated a preferred embodiment of the invention.

In the drawings, Figure 1 represents in side elevation the head of a lasting machine provided with my invention; Fig. 2 is an enlarged fragmentary detail thereof, partly in side elevation and partly in section, for more clearly illustrating the clamping feature of the invention; Fig. 3 is a transverse sectional view taken on the line 3—3, Fig. 2; Fig. 4 is a similar sectional view taken on the line 4—4, Fig. 2; Fig. 5 is a cross sectional view on the line 5—5, Fig. 2; and Fig. 6 is a cross sectional view on the line 6, Fig. 2.

Inasmuch as I have herein chosen to illustrate my invention in connection with the kind of lasting machine set forth and duly claimed in my Patent, No. 938,512, patented November 2, 1909, it is unnecessary for me to explain all the movements and constructional details, operation and advantages of the machine. Using the same reference numerals as in said patent, it is sufficient to say that the pedestal 1 supports a table 2 in whose bearing brackets 3 are journaled a driving shaft 4 and counter shaft 5. The wiper plates 24 are supported

in the outer slotted ends of crossed levers 23 pivotally mounted at their intersection on the lower end of a post 22 mounted on the outer end of a push bar 18 which slides in a rocker bar 16 and has its cam roll 19 arranged to travel in a cam groove 20 of a cam 21 secured on said counter shaft 5. A spreader and clamp has a forearm or lower part 40 pivoted to an upper part 38, controlled by springs 39, 42 and actuated by a push rod 35 whose roll 36 engages a peripheral cam 37, all as explained in said patent. The rocker bar 16 is pivoted at 17 and has its roll 15 traveling in a cam path 14. The wipers are given a yielding movement by a spring 33 on a rod 28, and closing tendency is given the spreaders by springs 46. The rest 69 is carried by a post 63 yieldingly supported by an intermediate pivoted lever 66 and spring 72, said lever having its cam roll 67 actuated by a cam 68 on the shaft 5, a locking device being shown at 65, 89 and 91 in connection with teeth 90 on said post 63. All these details and others not mentioned may be and preferably are the same as in my aforesaid patent.

Overhanging the bottom 100 of the shoe and last, which are indicated at 101, is a branching support which co-operates with and in opposition to a rest 69 to position and support the shoe, with the functions and advantages already set forth as constituting the chief element of my present invention. For convenience, this stop supporting member is mounted on an intermediate pivoted lever 49 whose roll 50 is actuated by edge engagement with a cam 51. Mounted for vertical movement in the front end of said lever 49 is a toothed post 54 adjusted up and down by a worm wheel 55 pivoted in said lever 49 to be hand operated for raising and lowering the post 54. At its lower end the post 54 is provided with an arm 102 terminating at its lower end in a gripping clamp 103 and at its upper end provided with locking means and adjusting means (both of said functions being preferably embodied in a single mechanism), herein shown as comprising a worm 104 having a head 105 to be turned by the hand and engaging a worm wheel or worm teeth 106 on the upper end of the arm 102, which is transversely pivoted at 107 in the lower end of said post. Also suitably mounted in said post, preferably just below the arm 102, is a rearwardly extending arm 108 having at its rear end a gripping clamp in the form of a foot or shoe 109 preferably serrated and shaped to fit the slope of the shank already alluded to, as clearly shown in Figs. 2 and 4. This shank gripping clamp is provided with means for adjusting it and locking it relatively to the post 54, and preferably with means for

changing its position laterally, said three functions being preferably embodied in a single device, although it will be understood that each may be embodied in a separate scope within the scope of my invention. As herein shown, the post-engaging end of the arm 108 is straight, and is provided with transverse serrations or teeth 110 to engage similar serrations or teeth 111 in the lower slotted end of said post, which is provided at one side with a threaded thumb screw 112, herein shown as having a conical end 113, Fig. 3, in position to engage against the under side of said arm so as to wedge the arm upward firmly in locked position when the thumb screw is turned inwardly and yet permit the arm to be rotated axially or moved longitudinally when the screw is turned outwardly to a sufficient extent. The gripping clamp or foot 109 is preferably adjustable angularly with reference to the arm 108, being for this purpose pivoted on said arm 114 and provided with a worm wheel or sector 115 engaged by a worm 116 supported by said arm and provided with a milled head 117 by which it may be operated. At its upper end, the post 54 carries an annular sleeve 118 to which is pivoted at 119 a rearwardly and downwardly extending arm 120 shaped at its lower end to conform approximately to the heel of a last, said lower end being preferably provided with a friction pad, herein shown in the form of two blocks 121 of rubber, Fig. 5, set angularly to each other. The arm 120 is normally held outward in approximately correct position by a spring 122 on a rod 123 loosely held to the post 54 by engagement with a ring or eye 124, said rod 123 passing through the arm 120 and adjustably secured by a hand wheel 125 in threaded engagement with the threaded outer end 126 of said rod. The sleeve 118 is one convenient means of permitting the arm 120 to be swung laterally so as to conform readily to right and left lasts and to extreme crooked lasts, said sleeve also permitting up and down movement so as to permit the rubber pad 121 to engage the heel at the right point for different kinds of lasts, *i. e.* high heels, low heels, etc. The connection of the rod 123 with the post also permits these various movements.

In use, the operator adjusts the arm 102 up or down as required in accordance with the spring of the last. The next adjustment to be explained is the adjustment whereby the clamp 103 is caused to act as a locating point for the toe lasting. I regard this as a feature not only novel, in my invention, but of considerable practical importance. As the most convenient means of securing the result mentioned, whereby the last is positioned and supported in the last-

ing machine in exactly the correct position with reference to the wipers 24 and other lasting mechanism so that the lasting operation is performed on the shoe to the best advantage, I prefer to have the arm 102 extend rigidly from the post 54 and non-adjustably with relation thereto (excepting for the angular adjustment 104, 106), and to secure the proper positioning and engagement of the clamp 103 with relation to the toe of the last by means of the adjustment of the shank clamp 109 (supplemented preferably by the heel clamp). The proper position of this toe clamp is indicated in Fig. 6, and in order to secure the engagement of the toe clamp in this "locating point", I loosen the screw 112 so as to permit the arm 108 to be adjusted longitudinally, and then I shift said arm lengthwise toward or from the clamp 103 so that the shank clamp 109 will compel the last to assume the proper position with relation to the toe clamp 103 when the last is put into the machine and the three clamps 25 or supports 69, 103, and 109 are brought into mutually clamping engagement with the last and the shoe thereon. Having adjusted the arm 108 lengthwise and thereby secured the proper position of the toe clamp 30 103 with reference to the toe of the last, said arm is clamped by its clamping screw 112, being first rocked to the right or left to such extent as may be required in accordance with the particular form of shank which it is to engage. Not only is it desirable to shift this shank engaging foot 109 slightly to accommodate rights and lefts, but some lasts slope more than others, and accordingly my invention aims to permit the foot of the 35 gripper to conform to whatever particular shape of last may be used. In Fig. 4, I have purposely shown a somewhat extreme shape in order to bring out more clearly this feature of my invention. Also, as the slope 40 of the shank differs almost infinitely, the foot 109 will be adjusted angularly with reference to its arm 108 by turning the worm 116 one way or the other until the gripping surface of the foot 109 conforms 45 accurately to the slope of the shank of the particular last. Having thus adjusted the two clamps 103, 109 with reference to the bottom clamp or support 69 so as automatically to hold the shoe in proper position for 50 lasting, the shoe and last are put into the machine, which is started (as explained in my patent aforesaid) thereby causing them to be gripped and held firmly in the position shown in Fig. 1. The operator then 55 swings the heel clamp up or down and to the right or left as the case may be, into proper engagement with the heel end of the shoe and last, and clamps the heel clamp firmly in position simply by turning up the hand wheel 125, all of the adjusting

movements thus far mentioned being accomplished instantly by the experienced operator. Thereafter, as the lasting proceeds, the rearward thrust is largely taken by the shank gripping clamp 109, supplemented by the heel clamp, and as the last is moved vertically by the automatic lasting mechanism, the heel clamp is not permitted to shift with reference to the shoe because it necessarily moves up and down with the shoe, being carried directly by the lever 49 in accordance with which the vertical movements of the shoe take place.

As the heel clamp or gripper is not clamped until after the automatic clamping of the work by the three members 69, 103, 109 has taken place, the operator is at liberty to set said heel clamp up hard by means of the hand wheel 125 by a quick movement without danger of disturbing the shoe. This permits the heel clamp to relieve the shoe of considerable of the endwise strain to which it has been heretofore subjected, and, as the heel clamp travels up and down with the arm 49, said heel clamp aids materially in maintaining the shoe at the same angle all through the lasting operation. A further advantage is that the shoe, although thus held rigidly in its lengthwise and angular position with relation to the machine, is nevertheless held yieldingly as to vertical movements, in connection with the yielding supporting mechanism explained more at length in my aforesaid patent. Thus, as the wipers, in their wiping movement, require, because of extra thickness of leather or for any other reason, that the shoe should yield downwardly, the mechanism at once permits of this downward yielding movement without in the slightest disturbing or releasing the unyielding grip of the gripping mechanism, which continues to maintain an unremitting grip on the shoe at the four important points. Also, as the toe clamp is brought (by the adjustments previously explained) into exactly the right relation to the toe for securing the best lasting results, the wipers are thereby permitted to engage the leather with more certainty of an even grip or pressure than in my patented mechanism referred to. This tends to insure an even uniform pull or strain on the leather all around the toe inasmuch as the clamp 103 constitutes a locating point for the wiping action (as well as for all other movements of the complete lasting operation). It will be understood also that the relative adjustment toward and from each other of the members 103 and 109 accommodates the machine to different sizes and different styles of lasts. Also by gripping the last at the three points mentioned, to wit, the slope of the shank, the toe, and the hollow on top of the foot, there is a two-fold advantage,

first a certainty of position is secured which insures accuracy of lasting, and second, the leather of the vamp which is to be lasted is left in position to respond to the best advantage to the action of the wipers and various operations of the lasting process.

It will be understood that the wiping action and various lasting movements may be of any usual or preferred kind, preferably as set forth in my patent aforesaid, which movements will be understood from said patent and for that reason are not herein set forth in detail.

Having described my invention, what I claim as new and desire to secure by Letters Patent is,

1. In a lasting machine, the combination with toe lasting mechanism, of means to hold the last, comprising a clamp mounted to present a transverse backing for engaging, and restricted to, the shank slope of the last in a direction to resist endwise thrusts thereon from the toe lasting mechanism, said clamp leaving the bottom of the last forward of said shank slope unoccupied and unengaged, and other clamping means positioned for external engagement against the outer surface of the shoe being lasted and arranged to oppose said transverse backing of the first mentioned clamp and co-operative with the latter to firmly hold the last.

2. In a lasting machine, the combination with toe lasting mechanism, of means to hold a last, comprising a clamp mounted to present a transverse backing for engaging the shank slope in a direction to resist endwise thrusts of the toe lasting mechanism, said clamp being adjustable for fitting against the shank slopes of different lasts, and other clamping means arranged to oppose said transverse backing and co-operative therewith to firmly hold the last.

3. In a lasting machine, the combination with toe lasting mechanism, of a clamp to engage the shank slope of a last in a direction to resist endwise thrusts of the toe lasting mechanism, said clamp being adjustable transversely and lengthwise of the shank slope to properly embrace the same, and to engage lasts of different sizes, and other clamping means co-operative therewith to firmly hold the last in operative position.

4. In a lasting machine, the combination with means for stretching and shaping the vamp over the toe of a last, of means for engaging the shank slope of the last for adjusting the last endwise relatively to said stretching means.

5. In a lasting machine, the combination with means for stretching and shaping the vamp over the toe of the last, and a last clamp, of means engageable against the shank slope of the last, for adjusting the last endwise with reference to said stretch-

ing means, said adjusting means being arranged to coöperate with said last clamp to position and rigidly hold the last.

6. In a lasting machine, the combination with means to stretch and shape a vamp over the toe of the last, and clamps for the toe and top of the foot of the last, of means for engaging the last at the shank slope to adjust the same lengthwise with relation to said stretching means, said adjusting means being arranged to coöperate with said clamps to rigidly clamp the last in adjusted position.

7. In a lasting machine, the combination with clamps to engage the toe portion and the top of the foot of a last respectively, and wipers operative on the toe portion, of a shank clamp to engage the shank slope of the last, said clamp being adapted to coöperate with the clamps aforesaid to rigidly hold the last against endwise thrusts imparted by said wipers.

8. The combination with means to clamp the bottom toe portion of a last, of an adjustable abutment mounted to present a transverse backing to the bottom shank slope portion and to act in a direction angular with relation to said toe clamping means, and a third clamping member mounted to engage the top portion of the last in a position and direction to oppose said toe clamping means and said abutment to firmly hold the last and resist thrusts of the lasting mechanism.

9. The combination with means to grip the toe portion of a last, and toe lasting mechanism, of a backing clamp, arranged to present a transverse backing to the bottom shank slope portion, said clamp being laterally adjustable to conform to the last shape.

10. The combination with means to support the toe portion of a last, and toe lasting mechanism, of a backing clamp to engage the bottom shank portion of the last, and means permitting adjusting of said clamp in two planes at right angles to each other to conform to the last shape.

11. The combination with toe lasting mechanism, and a support for the top of the last, of a toe clamp, and a clamp for the shank slope of the last, said clamps having a common mounting and adjustment.

12. The combination with toe lasting mechanism, and a support for the top of the last, of a toe clamp, and a rearward clamp for the last, said clamps having a common mounting and adjustment, and means for adjusting either clamp on said mounting separately.

13. In a lasting machine, the combination with means for supporting the front portion of a last, comprising three opposed clamps separately mounted to act in converging directions, one thereof being the shank slope clamp, and toe lasting mechanism, of means

presenting an endwise backing for clamping the heel of the last, said means being coöperative with said front support to clamp the last and withstand lasting thrusts.

5 14. In a lasting machine, the combination with movable means for supporting and clamping the toe portion of the last, and toe lasting mechanism, of a backing to engage the heel, said backing having a mounting arranged to participate in the movements of the last and its toe support.

15. The combination with movable means for supporting and clamping the toe portion of a last, and toe lasting mechanism, of 15 a heel backing having a mounting in common with and movable with said toe clamp, and an adjustment separately therefrom.

16. The combination with a support for the top of a last, of a toe clamp, a shank 20 slope clamp, and a heel clamp, said clamps having a common movable mounting and independent adjustments.

17. In a lasting machine, a last top support, a toe clamp, and a clamp arranged to 25 press transversely against the shank slope

of the last, said clamps adapted to coöperate with said top support to rigidly hold the last against lasting thrusts.

18. In a lasting machine, a support for the last top, an opposed toe clamp, a shank 30 slope clamp arranged to offer a transverse backing to the last against lengthwise lasting thrusts, and a heel clamp, said clamps arranged to coöperate with each other and with said top support to rigidly hold the 35 last.

19. In a lasting machine, a support for the top of the last, a toe clamp, a shank slope clamp, and a heel clamp, said clamps and support having movable mountings so 40 arranged that movements in the lasting operation will be imparted to all in like manner simultaneously.

In testimony whereof, I have signed my name to this specification, in the presence of 45 two subscribing witnesses.
